WAX PAPER MACHINE

Le Roy F. Carkhuff, Morris, Ill., assignor to Self-Locking Carton Co., Chicago, Ill., a corporation of Illinois

Application August 17, 1935, Serial No. 36,732

3 Claims. (Cl. 242—56)

The present invention pertains to devices for producing rolls from webs of various materials, and has particular reference to an improved machine for forming rolls from webs such as of wax paper.

It is customary to market wax paper in small rolls adapted for household use, and as the wax paper is produced in large rolls, it is necessary to unwind the large roll and produce therefrom a plurality of smaller rolls of household size.

A principal object of the present invention is the provision of an improved device for producing in a highly efficient manner small rolls from a traveling web of material.

An additional object is to provide a substantially continuously operating roll-forming machine adapted to pick up and secure the forwardly traveling end of a web of paper or similar material and to wind the web into roll form.

A still further object is the provision of a roll-forming machine having a centrifugally operated winding means for securing the loose end of a traveling web.

These and other objects will be evident upon a consideration of the following specification and by reference to the accompanying drawings, in which

Fig. 1 is a side view of a device constructed in accordance with my invention;

Fig. 2 is a view of the machine shown in Fig. 1 taken from the opposite side thereof;

Fig. 3 is a top view of the machine shown in Fig. 1;

Fig. 4 is a fragmentary end view of the machine showing in greater detail the roll-forming unit thereof;

Fig. 5 is a fragmentary side view showing the roll-forming drive and break mechanism;

Fig. 6 is a view showing the cam arrangement for actuating the winding rolls;

Fig. 7 is a detailed view, partially in section, showing the roll-winding head;

Fig. 8 is an end section of a winding roll;

Fig. 9 is a fragmentary end view of a roll-forming unit;

Fig. 10 is a sectional view of the unit shown in Fig. 9 taken along line 10—10 of Fig. 11;

Fig. 11 is a cross-sectional view taken along line 11—11 of Fig. 10; and

Fig. 12 is a view similar to Fig. 11 showing the web-engaging units in retracted position.

As shown in the drawings, the device is constructed about an upstanding frame member 10 having a power-imparting motor 11 positioned

therebeneath. Preferably, the motor is provided with a conventional magnetic brake device.

At the feed end of the frame 10 a relatively large roll 12 of a web 13 is rotatably mounted by means of the shaft 14 and U-shaped bearing members 15 mounted on the frame. The web 13 passes over a roller 16 mounted on an upstanding frame unit 17, and beneath a second roller 18, which is carried on a swing arm 19. The swing arm 19 is pivoted to the frame 10 at 20 and has a lower arm 21 which is connected to a pivoted L-shaped brake-actuating arm 22 by means of rod 23. Arm 22 is pivoted to the frame member 10 at 24 and has an upper arm 25 connected to the jaws 26 and 27 of a brake mechanism by means of rod 28 and lever 29, as shown in Fig. 2. As long as the web 13 remains taut the lever 19 is maintained in upraised position and the jaws 26 and 27 are spread apart sufficiently to permit free rotation of the roll 12. Breakage of the web 13 causes the lever 19 to fall downwardly and the jaws 26 and 27 are brought together to stop rotation of the roll 12.

The web 13 passes from the roller 18 between an upper rubber-faced feed roll 30 and a lower steel feed roll 31. The lower feed roll has a shaft 32, each end of which is journaled in opposite frame units 33 mounted on the frame 10. A sprocket 34 is secured to one end of the shaft 32 and carries a chain 35. The other end of the chain 35 passes over a sprocket 36, which is mounted on shaft 37. The shaft 37 extends transversely of the frame member 10 and carries a pulley 38 upon which rides the belt 39, the latter being driven by motor 11, as shown in Fig. 2. The upper drive roll 30 has a shaft 40, each end of which is journaled in the oppositely positioned frame units 33. Spring members 41 maintain the upper draw roll in frictional engagement with the lower draw roll to provide the necessary driving power. One end of the shaft 40 has a gear 42 of a pitch diameter equal to the diameter of the roll meshing with a gear (not shown) keyed to shaft 32 and provided with a pitch diameter equal to the diameter of the lower roll. In this manner the two rolls are driven at the same peripheral speed, even though the rolls are of different diameters.

Beyond the draw rolls is a second web control unit which automatically stops the machine when the web breaks. This unit consists of a light weight arm 44 pivoted to the frame member 33 at 45 and having an upwardly extending circuit breaker arm 46 which is adapted

upon downward motion of the arm 44 to press against the lever 47. Lever 47 is pivoted to a stationary frame member 48 at 49. The upper portion of the lever 47 has a contact point 50 which engages a similar point 51 on stationary arm 52. The contact points 50 and 51 are normally maintained in contact by action of the spring 53 secured to the upper portions thereof. The circuit which operates motor 11 passes through the conduit 54 and the contact members 50 and 51 are wired in series in this circuit. Breakage of the web 13 causes the arm 44 to drop by gravity and the lever arm 46 presses the arm 47 outwardly so that the contact points 50 and 51 are broken and the motor stops.

As it is desirable to obtain access to the machine at the draw rolls for such purposes as threading the web through the machine, there is provided a hand-operated lever 55 by which arms 56 and 57 may be moved in a reciprocal manner to rotate shaft 58. Shaft 58 extends transversely of the machine and is provided with cam units 59. These cam units raise and lower the upper draw roll 30 in an obvious and well known manner.

After passing through the draw rolls the web 13 travels through the idlers 60 and into the roll-forming unit. This unit consists of rotatable winding rolls 61 and 62 which are secured at one of their ends to a revolving roll carrier frame 63, the roll 61 being carried by arm 64 and the roll 62 being carried by arm 65. The frame 63 is keyed to shaft 66 which is rotated by means of gear 67 and worm gear 68 meshing therewith. One end of the shaft 66 is journaled in the frame unit 69 and an intermediate portion of the shaft is journaled in the frame unit 70. Worm gear 68 is carried on a shaft 71 which is actuated by chain 72 and sprocket 40 wheels 73 and 74, the latter being secured to shaft 75. To the opposite end of shaft 75 is secured a pinion gear 76 which is driven by a similar pinion 77 carried on shaft 78. Shaft 78 is provided with a gear 79 meshing with a gear 45 80 on shaft 37. It will be seen that the drive arrangement for shaft 66 is such that a relatively slow rate of rotation is provided.

Shaft 66 also carries a cam 81, and this cam acts to operate a cutting unit for severing the web 13 when the roll of the desired size has been formed. A cam arm 82 having cam rollers 83 and 84 travels on the cam. The opposite end of the arm 82 is secured to shaft 85 which carries a knife arm 86. As the cam 81 rotates, the rollers are tripped by the cut-away portions 87 and 88 and the weight of the cam arm and the knife arm 86 causes the serrated knife 89 which is attached to the latter to fall into cutting relation with the web 13, as will be seen in Fig. 5. The knife 89 cuts the web adjacent the L-arms 90 and 91 which are secured to an extension of the shaft 66. To protect the cam and cam rollers against undue jar when tripped by the cam, an extension 92 is secured to the end of the cam roller arm 82, and a nut 93 secured to this extension engages the sleeve or journal 70 to prevent the rollers 83 and 84 from striking the high portion of the cam. Shaft 85 is assisted in its cutting operation by a spring 94 which insures rapid operation of the cutting knife.

Two cam rollers are employed due to the sharp angle of the cut-away portions of cam 81 thereby preventing the first roller from being caught behind the edge of the cam as the rollers reach the outside of the cam. That is, the second cam

roller lifts the first cam roller over the sharp edge of the cam as the latter rotates.

The angle bars 90 and 91 do not cut the paper, but do maintain the web in taut condition at the moment of impact of the serrated knife 89.

The shaft 85 also carries an arm 95 provided with a transversely extending shaft 96 and a series of rubber-faced rollers 97. As shown in Fig. 5, the forward edge of the severed web 13 is pressed downwardly against the winding rolls 10 at the cutting interval by the rubber-faced rollers 97, thereby initiating the winding of an additional roll.

The winding rolls 61 and 62 are provided with outer barrel portions 98 and these portions have four slots 99 extending longitudinally thereof. End caps 100 form a closure for the winding rolls and space the barrel portions from the shaft sections 101. Interiorly of the barrel portions 98 are shafts 101 which are grooved to receive longitudinally extending bearing rods 102. Mounted to the outer portions of the bearing rods 102 are the notched gripper knives 103, as will be seen in Figs. 9, 11 and 12. Bearing rods 102 are free to rotate in their slots in the shaft 101 and as the winding rolls are rapidly rotated the gripper knives 103 are caused to project outwardly through the openings 99 in the manner shown in Fig. 11. In their inner and inoperative position the knives 103 recede to the position within the outer shells 98, to allow removal of the roll of paper from the winding mechanism by hand.

The barrel portions 98 have abutting portions 104. The winding units are mounted on the arms 64 and 65 by means of ball bearing units 105 and 106 which permit the winding units to be rotated easily and rapidly. Adjacent the ball bearing units 106 are the brake drums 107 which are keyed to the shafts 101 in the manner shown in Fig. 7. The ends of the shafts 101 are provided with a drive mechanism. This drive mechanism includes an outer pulley portion 108 into the central portion of which is secured a bearing sleeve 109, the latter being free to rotate on shaft 101. Adjacent and rotating with the pulley 108 is another pulley portion 110. Bolts 111 extend through the pulley portion 110 and screw into pulley 108. These bolts carry clutch plates 112. On the end of shaft 101 is keyed an internal clutch plate holding member 113 through which extend bolts 114. These bolts carry clutch plates 115, and the latter are in interleaved relation with respect to plates 112. The frictional engagement of these two sets of clutch plates is controlled by regulation of screws 116 bearing on springs 117, the latter pressing against the clutch plates as shown in Fig. 7.

As the shaft 66 is rotated, the pulley units 108 and 110 will come in contact with the drive belt 60 118 as shown in Fig. 2, thereby causing the winding unit to rotate rapidly. This belt is mounted about a pulley 119, and the latter is keyed to a shaft 120 which is driven from sprocket 121 by the chain 122. Chain 122 is driven by sprocket 123 mounted to shaft 37. The belt 118 passes about an outer guide pulley 124 and beneath a slack pulley 125 carried on the arm 126. The slack pulley is maintained in engagement with the belt by means of a pull spring 127, thereby insuring that the tension on the belt is substantially uniform at all times and providing for variations in the effective length of the belt.

The serrated knife grippers 103 are thrust outwardly by the centrifugal action accompanying

rotation of the winding units and engage the forward edge of the traveling web. Continued rotation of the winding unit causes the desired length of the web to be wound about the barrel 98 of the winding unit. By the time the winding unit reaches the position shown in Fig. 5 the desired amount of the web has been wound into roll form and the cutting unit is tripped by the cam 81. At this time the brake drum 107 which is keyed to shaft 101 engages the stationary brake band 128, thereby stopping rotation of the winding member. As the brake drum 107 is keyed to shaft 101, the latter is held against rotation when the drum 107 is in contact with the brake shoe 128. The belt 118 continues to rotate the pulley portions 108 and 110 for a short period of time after the brake shoe is reached. The engagement of the braking elements is sufficient to hold the inner clutch plates 115 against rotation, thereby permitting the outer clutch plates 112 to 20 slip without imparting rotation to shaft 101.

Brake shoe 128 is mounted on a frame member 129 and is made resilient by means of springs 130 and 131.

As the winding operation is completed on the roll 61 the roll 62 has been brought into engagement with belt 118 as shown in Fig. 5 and the cycle of operation again is initiated.

In the operation of the device a web is passed from roll 12 above the roller 16 and beneath the braking unit roller 18. The amount of slack between the roller 16 and the draw rolls determines the position of the roller unit 18 and consequently the amount of braking or hold back of the roll. If the web slackens the arm 19 is depressed and a certain amount of braking is provided by the jaws 26 and 27 to insure the proper speed of rotation of the roll 12. The draw rolls progress the web past the idler or guide rolls 60 and into the roll-winding mechanism. Considering the position shown in Fig. 5 as the initial stage in the operation of the device the severed end of the web is pressed downwardly adjacent the barrel 98 of the winding roll and as the latter is whirling at a rapid speed the knife grippers 103 having serrated tooth edges strike the trailing edge of the paper and penetrate sufficiently to grip the paper and insure its being wound upon the roll. The cam 81 causes the cutting unit to raise and the winding roll 62 is progressed in a circular path about shaft 66 to a position adjacent the brake shoe 128, this position being indicated by the roll 61 in Fig. 5. At this time the desired amount of the web will have been wound into roll form and the cutting unit will again descend to sever the web and to start the repetition of the cycle of winding and cutting.

Engagement of the brake drums 107 of the winding rolls with the brake shoe 128 during the inoperative position of the winding unit allows a sufficient period of time for the operator to remove the wound roll by hand. As the rotation of the winding roll is stopped by the brake shoe 128 the gripper knives 103 retract within the shell 98, thereby permitting easy withdrawal of the roll from the free end of the winding roll. In one embodiment of the device, the speed of operation is maintained so that an operator will have time to grasp a wound roll of wax paper, withdraw it from the barrel 98, and place in a

suitable container by the time the next wound roll is in position for removal. Thus, it will be seen that the winding units rotate quite rapidly about the shafts 101 while the arms 64 and 65 rotate relatively slowly about the shaft 65. The angle irons 90 and 91 rotate with the shaft 66 and present a taut web to the blade 89 at the cutting interval. The severed end of the web is maintained in contact with the whirling winding units for a sufficient period of time to allow the gripper knives to engage the web. Thus, the web always is maintained in its extended position, and the cutting and winding operation is continuous. The device is simple in construction and permits of rapid formation of rolls with a minimum loss of time due to such factors as web brakes and adjustments.

An additional advantage of my improved roll-forming device lies in the relatively high speeds of operation possible. The web may travel at 20 a speed of approximately 750 feet per minute, and the individual rolls may be of a length of the order of 30 to 60 feet. Thus, 25 or 30 rolls or more may be formed per minute. The winding sprocket will make one revolution for each two 25 rolls formed. As the roll-winding units may have a diameter of less than two inches, it will be seen that the units rotate at a high speed which may be of the order of 1850 R. P. M.

It will be seen that many changes may be 30 made in the device described herein for purposes of illustration and explanation, and all such changes and modifications coming within the scope of the invention are intended to be included in the appended claims.

I claim:

1. In a device for forming rolls from a web of paper, means for feeding a traveling web, a central shaft rotatable at a relatively slow speed and carrying opposed cutting knives, relatively rapidly rotating winding units mounted on said shaft and movable thereby adjacent the path of travel of said web, means on said relatively rapidly rotatable and winding units for grasping the end of said web, and an additional cutting unit co-operable with said first mentioned cutting knives to sever said web when a roll has been formed.

2. In a device for forming rolls from a web, means for feeding a web, a continuously and relatively slowly rotating carrier adjacent the path of travel of said web, a plurality of winding rolls on said carrier, means for rapidly rotating said rolls, means for attaching the end of the web to said rolls, knife members mounted on said carrier and rotatable therewith, and a reciprocal cutting unit co-operable with said knives for cutting said web between adjacent rolls.

3. In a device for forming rolls from a web, means for feeding a web, a relatively slowly rotating carrier adjacent the path of travel of said web, a plurality of winding rolls on said carrier, means for rapidly rotating said rolls, means for attaching the end of the web to said rolls, a cutting member associated with said carrier, and a reciprocal cutting member independent of said carrier and co-operable with said first cutting member for severing said web between adjacent rolls.

LE ROY F. CARKHUFF.
